(57) **CLAIM**

The ornamental design for a medal toy, as shown and described.

DESCRIPTION

FIG. 1 is a front perspective view of a medal toy;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines are included for the purpose of illustrating the portions of the medal toy that form no part of the claimed design.

1 Claim, 4 Drawing Sheets(56)
